UNITED STATES PATENT OFFICE.

ISAAC UNSWORTH, OF CLEVELAND, OHIO.

LINING FOR THE THROATS OF FIREPLACES.

1,273,695.

Specification of Letters Patent.

Patented July 23, 1918.

Application filed August 14, 1916. Serial No. 114,732.

To all whom it may concern:

Be it known that I, ISAAC UNSWORTH, a citizen of the United States, and resident of Cleveland, in the county of Cuyahoga and State of Ohio, have invented certain new and useful Improvements in Linings for the Throats of Fireplaces, of which I hereby declare the following to be a full, clear, and exact description, such as will enable others skilled in the art to which it appertains to make and use the same.

The invention comprises a hollow lining or casing insertible in the throat of a fire place and providing in itself all the flue connection required to convey the products of combustion from the fire place into the chimney.

It is designed to be set directly over the fire place and rest upon the side walls thereof. It further comprises a correctly proportioned hollow casing having properly proportioned parts so designed as to promote a perfect draft and good combustion in the grate, and contains a vertical opening or passage in the rear, communicating with the chimney flue and inclined sides which constitute the lining proper which are positioned over the fire place and which direct the products of combustion into the vertical passage and thus to the chimney.

It also includes a damper pivoted in the vertical passage and positioned to control the passage of the products of combustion from the hood portion into the flue.

The invention further comprises the combination and arrangement of parts and construction of details hereinafter described, shown in the accompanying drawings and specifically pointed out in the claims.

In the accompanying drawings Figure 1 is a vertical section of the fireplace lining and chimney flue; Fig. 2 is a front elevation of the fireplace showing the lining and attached parts in dotted lines embedded in the walls; Fig. 3 is a perspective view of the lining from the rear showing the vertical connecting passage between the lining and chimney flue, and flange which rests upon the walls of the fire place Fig. 4 is a perspective view of the front of the said lining.

In these views A is the fireplace opening; A' the walls; B is a metal plate preferably an angle plate over the fire place opening which supports the brick work above; C is the lining or hollow casing which is pro-

vided with a marginal flange C' upon its lower front and side edges; the front flange rests upon a second angle plate D, and the side flanges rest upon the side walls of the fire place.

The front wall E and side walls F of the lining are inclined toward the upper end, and the rear wall G is vertical, and with walls E and F approaching a hollow wedge in shape, and the rear wall is provided with a vertical opening preferably central with which a vertical passage H in the rear communicates.

The front wall of this passage is cut away to connect the lining and vertical passage, and the lower end of the vertical passage is closed by means of the narrow bottom wall H' which compels all products of combustion to be drawn first through the lining and thence directed into the central vertical passage H.

A single damper or valve I is hinged at the rear lower edge of the vertical passage and by alternately directing it to engage with the front wall of the lining and rear wall of the vertical passage the draft can be easily controlled.

This damper can be operated by means of a jointed rod J attached thereto, which passes through the front wall of the fire place, and the outer end of this rod can hang down over the wall if desired.

The walls of the vertical passage are designed to rise high enough in the chimney flue to contact with the fire brick or lining L to prevent injury to the brick work.

A lining of this character is a long step toward practical and efficient work in constructing a fire place, since it eliminates all inexperienced and rough mason work and is proportioned and balanced to provide a proper draft in the chimney.

The lining and vertical flue are completely embedded in brick work and when completed they are not visible, and the fire place and mantel piece can be completed in any form of ornamental design desired.

The flue member engages the rear wall of the chimney flue and the rear wall of the fire place connects with the lower rear edge thereof.

The lining and vertical flue member are unitary in structure but can be made in sections rigidly connected together if desired, and the material of which it is composed may be cast or sheet metal or fire brick.

terra cotta or similar substance, the requirement being that it shall be so constructed as to be fire resistant and insertible by unskilled labor in any fire place.

5 It can also be made in standard sizes for immediate use by builders.

Having described the invention what I claim as new and desire to secure by Letters Patent is:

10 1. An independent lining for the throat of a fire place, comprising a wedge shaped lining member having inclined front and side walls, and a vertical rear wall, said rear wall having a vertical opening, and a vertical flue member having an opening in its front wall communicating with the vertical opening in said rear wall of said lining, said lining and rear flue member mountable upon the walls of the throat of said fire place, and a swinging 15 damper hinged at the rear lower edge of said flue member, and means for alternately engaging the upper end of said damper with the front wall of said lining and the rear wall of said flue member.

15 2. A lining for the throat of a fire place,

20 2. A lining for the throat of a fire place,

comprising a wedge shaped lining member having inclined front and side walls, and a vertical rear wall, said rear wall having a vertical opening, a vertical flue member 25 having an opening in its front wall communicating with the vertical opening in said rear wall of said lining, said lining and rear flue member mountable upon the walls of the throat of said fire place, and a swinging 30 damper hinged at the rear lower edge of said flue member, and means for alternately engaging the upper end of said damper with the front wall of said lining and the rear wall of said flue member.

35 In testimony whereof, I hereunto set my hand this 23d day of June, 1916.

ISAAC UNSWORTH.

In presence of--

Wm. M. MONROE.

C. M. KINNIGAN.
